CLAIM

The ornamental design for a mixing ball, as shown and described.

DESCRIPTION

FIG. 1 is a top perspective view of a mixing ball;
FIG. 2 is a top side perspective view of the mixing ball;
FIG. 3 is a front view of the mixing ball;
FIG. 4 is a rear view of the mixing ball;
FIG. 5 is a top view of the mixing ball;
FIG. 6 is a right side view of the mixing ball; and,
FIG. 7 is a left side view of the mixing ball.
The broken lines represent portions of the mixing ball that form no part of the claimed design.
